RECOIL REDUCING DEVICE FOR FIREARMS

Frank H. Seeley and Edward W. Petri,
Fort Plain, N. Y.

Application March 23, 1949, Serial No. 83,002

1 Claim. (Cl. 89—14)

1

Our invention relates to firearms and particularly to firearms of the type, such as rifles and shotguns, which are fired from the shoulder. Firearms of this type, except those of the smallest gauges and calibers, produce, when discharged, a recoil force of substantial magnitude which in all instances is unpleasant and, where many rounds are fired consecutively, as in trap, skeet, or target shooting, severely bruises the shoulder of the shooter.

The principal object of our invention is to provide an extremely simple device which can be built as a part of, or readily attached to, any rifle or shotgun, and which will function substantially to reduce the recoil force developed upon a discharge of the firearm.

We accomplish this object by means of the novel elements and the combinations and arrangements thereof described below and illustrated in the accompanying drawing in which—

Fig. 1 is a fragmentary, side elevation view of a rifle or shotgun, with portions broken away, illustrating our device, in longitudinal section, attached thereto with the parts in normal position before firing;

Fig. 2 is a view similar to Fig. 1 but showing the parts in the position to which they move when the gun is fired;

Fig. 3 is a view of Fig. 1 as seen through the plane 3—3; and

Fig. 4 is a fragmentary longitudinal section of a modification of our device.

Referring to the drawing, and first to Figs. 1, 2 and 3—

1 is the fore-end and 2 the barrel of either a rifle or shotgun. Secured to the under side of the barrel, by brazing or other means (not shown), and in spaced, substantially parallel-disposed relation thereto is our recoil reducing device which is represented generally by the numeral 3.

The device comprises an elongated tube 4 which, as illustrated in Figs. 1 and 2, is internally threaded at each end and closed at the front by the threaded plug 5 and at the rear by the threaded plug 6. The tube 4 may be about 6 or 7" long and of an outside diameter approximating the outside diameter of the gun barrel. The inside diameter of the tube, in the case of a shotgun, may approximate the inside diameter of the barrel of the gun but, in the case of a rifle, the inside diameter of the tube will generally be substantially larger than the inside diameter of the barrel. Slidably mounted in the tube 4 is a piston 7, having a head 8 and an elongated skirt 55

2

9, and which is of a mass or weight, depending upon the gauge or caliber of the gun, somewhat in excess of the mass or weight of the shot charge or bullet to be fired therefrom. The movement of the piston to the rear of the tube 4 is limited by the projection 10 on the plug 6, or other suitable means, so that a space 11 is always maintained between the head of the piston and the plug 6 when the piston is in its rearmost position.

10 A passage 12 provides communication between the bore of the barrel 2 and the space 11. A light, helical compression spring 13 is biased normally to hold the piston 7 against the projection 10 of the plug 6.

15 The spring 13 extends into the piston, as shown in Fig. 1, and is maintained substantially coaxial with the tube 4 by the projection 14 on the plug 5. The plug 5 is provided with passages 15 extending axially therethrough and providing communication between the interior of the tube 4 and the atmosphere. Intermediate its ends, the tube 4 is also provided with a plurality of ports or openings shown in Figs. 1 and 2 as circumferentially-spaced, longitudinally-extending,

20 25 slots 16 which provide communication, through the passage 12 and the tube 4, between the bore of the gun and the atmosphere after the piston 7, as it moves forwardly in the tube 4, has passed thereover.

30 As pointed out above, the parts are normally in the position shown in Fig. 1 but, when the gun is fired, some of the gas generated by the explosion of the powder, and which is ordinarily trapped in the barrel of the gun behind the bullet or shot charge until the bullet or shot charge leaves the muzzle of the gun, will escape through the passage 12, as soon as the bullet or shot charge passes the opening from the barrel into said passage. This gas, which is under very high pressure, will enter space 11 in the tube 4 between the head 8 of the piston and the plug 6 and will drive the piston forwardly in the tube to the position shown in Fig. 2. Air, which would normally be trapped in the tube 4 in the space between the plug 5 and the piston 7, will be discharged through the passages 15 in the plug 5, and also through the ports 16 until the piston 7 moves past the ports. Thereafter, the air will be discharged only through the passages 15 in the plug 5, but after the piston 7 passes the ports 16, the gases resulting from the explosion of the powder will be discharged through these ports.

When the gun is fired, the inertia of the bullet or shot charge and the frictional resistance offered to its passage toward the muzzle of the gun

is sufficient to start the development of the recoil force which tends to move the entire gun assembly rearwardly a small fraction of an inch before the bullet or shot leaves the muzzle. The recoil force however, develops to a maximum when the bullet or short charge leaves the barrel or, in other words, at the time of the muzzle blast. Before the bullet or shot charge reaches the muzzle of the gun, and before the recoil force has developed to a substantial magnitude, the gases resulting from the explosion escape through the passage 12 as soon as the bullet or shot charge moves past the entrance thereto, and these gases entering the space 11 in the tube 4 will drive the piston 7 forceably forward against the compression of spring 13 until it strikes the front plug 5, as shown in Fig. 2.

Since the piston 7 is of substantial weight, when it strikes the plug in the front end of the tube 4, as shown in Fig. 2, the blow will tend to drive the entire gun assembly forward in the direction opposite the recoil force, thereby reducing the effect of the recoil on the shoulder of the shooter.

In Fig. 4 we have shown a modification of our device in which the tubular element 4 is provided with external threads 17 at the front end which cooperate with the internally threaded closure cap 18 having air passages 19 extending therethrough similar to the passages 15 in the plug 5. There is some advantage in using a closure cap of the type shown at 18 rather than a plug of the type shown at 5 since it provides a slightly longer forward run of the piston with the same length tube. The rear end of the tube 4 is closed by the threaded plug 20.

Extending longitudinally of the tube 4 and coaxial therewith is a cylindrical rod 21 which is merely supported in a recess 22 in the cap 18 and in a recess 23 in the plug 20. The head 24 of the piston 25 is provided with a centrally-disposed opening therein through which the rod 21 passes so that the piston has a sliding fit both in the tube 4 and on the rod 21. The rearward movement of the piston within the tube 4 is limited by the collar 26 on rod 21, and the piston is normally held against the collar by means of the light, helical spring 27.

Adjacent the plug 20, the tubular element 4 is provided with a passage 28 which is adapted to provide communication between the bore of the barrel of the gun and the tube when the device is brazed or otherwise secured to the barrel. The tube is also provided with gas discharge ports 29 which function in the same way as the ports 16 shown in Figs. 1 and 2 but which are here shown as round.

The lugs 30 and 31 which are brazed or otherwise secured to the tube 4 are adapted to be brazed to the barrel of the gun for securing our device thereto; and lugs 30 and 32 shown in Figs. 1 and 2 serve the same function. The device shown in Fig. 4 functions in the same way as explained above in connection with the device shown in Figs. 1 and 2, and therefore no further explanation seems necessary.

It will be obvious that, when the powder charge in any gun is ignited, the gas pressure developed in the barrel of the gun is very high and that this pressure diminishes as the bullet or shot charge travels through the barrel of the gun and the gas expands behind it. For this reason, it is advantageous to attach our device to the gun barrel quite close to the cartridge chamber in order to

take advantage of the higher gas pressure which develops in this zone.

From the foregoing and a consideration of the drawing, particularly Fig. 2, it will be apparent that both the spring 13 and the spring 27 are of such character that they do not prevent the piston 9 from striking the closure element at the forward end of the tube in which said piston is slideable. Furthermore, the ports 16 or the ports 29, through which the gases resulting from the explosion of the powder are discharged, are not opened until just before the piston 9 strikes said closure element. Thus, the piston 9 is driven under high pressure substantially throughout its forward movement.

While we have described our invention in its preferred embodiment, it is to be understood that the words which we have used are words of description rather than of limitation and that changes, within the purview of the appended claim, may be made without departing from the true scope and spirit of our invention in its broader aspects.

What we claim is:

25 A recoil reducing device for a firearm of the type which is fired from the shoulder; said device comprising an elongated, cylindrical tube, a rod within and coaxial with said tube, a piston of substantial mass in said tube slidably mounted 30 on said rod, means forming a closure for each end of said tube, a light helical spring around said rod cooperating with said piston for normally but yieldingly maintaining said piston adjacent one end of said tube, means cooperating 35 with said piston when in normal position for maintaining it in spaced relation to said adjacent end of said tube, and means on said cylinder adapting it to be secured to the barrel of said firearm in closely spaced, parallel disposed relation thereto; said tube being provided with a lateral opening in a zone intermediate the normal position of said piston and the end of said tube adjacent the normal position of said piston and adapted to communicate with a passage through 40 said barrel in a zone intermediate the ends thereof for the flow of gas from said barrel to said cylinder upon a discharge of said firearm when said tube is secured to said barrel, and also with openings adjacent the other end of said tube for the passage of air, and ports intermediate the ends thereof for the discharge of gas; said ports being disposed to provide communication between the interior of said tube and the atmosphere for the discharge of gas therethrough only when said piston is closely adjacent the end of said tube 45 remote from its normal position.
